PLURAL SWITCH COIN-CONTROL AND
CIRCUIT THEREFORSam May, Chicago, Ill., assignor of one-half to
Raymond T. Moloney, Chicago, Ill.

Application July 19, 1945, Serial No. 605,966

7 Claims. (Cl. 194—10)

1

This invention pertains to a coin control device for use in conjunction with various types of coin-operated or controlled machines, such as vending and amusement machines, the principal object being the provision of a control device especially suited for use with the so-called gravity type of coin testing chute, but otherwise of general application, and operating to receive an acceptable coin from such a chute and actuate certain control switches or the like in a manner which prevents defrauding the coin-controlled machine by certain expediences, such as the use of captive coins, and the like.

Viewed from another aspect, it is an object of the invention to provide a coin-control device which is compact, simple, and rugged, and which is of substantially flat shape analogous to the shape of a commonly used form of coin chute, and which is readily attached to such a chute as an auxiliary means for preventing certain types of fraud to which such chutes are vulnerable apart from their function in testing coins and rejecting spurious coin elements.

Further objects are the provision of a device of the class described and cooperating circuit control means which makes possible the elimination of numbers of control relays and associated wiring heretofore required in such machines; the provision of a small control unit in the nature of a coin chute, which, by reason of its size, shape, and arrangement of parts is peculiarly adapted to attachment to conventional coin testing chutes of the gravity or drop type; the provision of a control unit including an oscillatory coin-moving lever adapted to dispose a coin in a first position in which it may function for certain control purposes, and movable to shift the coin to a second position in which the coin may function for additional control purposes; the provision of combination control and coin-holding means cooperable with the oscillatable lever for positively securing the coin in the second control position; the provision of means acting responsive to movement of the said lever for positively dislodging the coin from the second control position; and the provision of means cooperating with a coin-controlled machine for causing operation of the oscillatable coin-moving lever responsive to the manipulation of an operating lever or the like associated with the coin-controlled machine.

Additional objects and aspects of novelty and utility residing in the invention relate to details of the construction and operation of the illustrative embodiment described hereinafter in view of the annexed drawings in which:

2

Fig. 1 is a side elevation of the novel control device in association with a conventional coin chute;

Fig. 2 is another side elevation oppositely viewed from that of Fig. 1;

Fig. 3 is a side elevation of the control device with the cover plate removed and parts shown in section;

Fig. 4 is a view similar to Fig. 3 showing the coin-moving lever in a different condition of operation;

Fig. 5 is a horizontal section along lines 5—5 of Fig. 3 and showing an operating solenoid for the coin-moving lever; and

Fig. 6 is a circuit diagram.

In the upper part of Fig. 1 is shown a conventional type of coin-testing chute 10 into which coins are deposited as at 11, such coins gravitating downwardly in this chute past various testing instrumentalities well known in the art and functioning to cause delivery of an acceptable coin to an exit passage from which the coin would ordinarily drop into a collecting receptacle.

The novel coin-control means is also in the general form of a chute 12, which is attached to the testing chute 10 by means of a bracket 13, as in Figs. 1 and 2, secured by bolt and nut means 14. As in Fig. 5, the control chute preferably consists of a pair of cover plates 15 and 16 spaced apart by plate members 17, 18, 19 and 20 (Fig. 3 also) to provide a coin passage 21 interiorly of the control unit, and the upper or entrance end of this passage is positioned to be in register with the exit passage from the testing chute (not shown), so that an acceptable coin C₁, as in Fig. 3, will gravitate from the testing chute into the passage 21 of the control chute.

Means for arresting a received coin at a first position in the control unit includes, as in Fig. 3, a lever 25 pivoted as at 26 in the coin passage interiorly of the control chute, this lever having an arcuate upper edge portion 27 normally in alignment with the coin passage 21 and onto which the received coin C₁ drops to occupy the position of coin C₂, lever 25 having an extended portion 28 flanking the coin-receiving edge 27 and adapted to engage the coin C₂ and move it from first to second position (occupied by a coin C₃ for example), when the coin moving means or lever 25 is pivoted to the advanced position shown in Fig. 4.

Control means operated by a coin at first position includes (Fig. 2) a switch 30 mounted on the rear outside face of the control chute and having normally open switch blades 31, 32, with

an offset projection 33 from blade 32 extending through an opening 34 in plate 15 into the coin passage so as to be engaged by a coin at the first station, i. e. coin C₂, and thereby cause switch blade 32 to be flexed into closed circuit engagement with its companion blade 31 for control purposes hereinafter described. This control operation of the coin at the first position or station is also illustrated in Fig. 5.

When a coin is moved by advance of lever 25 into the second position or station, as in Fig. 4, it will be seen that the extended part 28 of the lever will prevent any retraction of the coin, as by a wire or thread attached thereto, so long as the lever 25 remains in advanced condition.

Means for preventing retrograde movement of the advanced coin C₃ from second position includes an extension 40, Figs. 1, 3 and 4, projecting through an opening 41, Fig. 1, in plate or wall member 16 into the coin passage, and having an offset end portion bifurcated or forked to provide coin-engaging portions 42 which bear frictionally down upon the upper edge of any coin C₃ moved to second position by reason of the fact that the extension 40 is carried on the end of a spring blade 43, Fig. 1, biased with this object in view. The edge part 44 of the forked coin-engaging means 42 is slanted so that a coin moving from first position toward second position will tend to cam the holding means 40—42 upwardly until the coin can be forced under the forked portions 42 as in Fig. 4, whereby retrograde movement of the advanced coin is prevented when the lever 25 is restored to normal position.

Additional coin-holding means includes a notched or forked formation 45, Figs. 3 and 4, in the arcuate edge portion 27 of lever 25, so disposed as to underly the advanced coin when lever 25 is in normal position, as in Fig. 3. Thus, an advanced coin in second position, for example the coin C₃, is prevented from moving back toward first position and the first control switch means by the formations 42—45.

However, a coin in second position, for example the coin C₃ will be ejected from second position by a subsequent advance of the lever means 25 from normal position owing to the disposition of the rearward part 45a of the forked holding formation 45 on lever 25 and the tendency of this part 45a to force the coin from beneath of parts 42 and the fact that the remaining portion 45b of the forked portion 45 tends to drop away from beneath the coin by angular displacement as lever 25 pivots. As a result, a coin ejected from second position will gravitate into an exit passage 22 formed by a small plate element 20 and the lower projection 11a of spacer plate 17, as illustrated by the coin C₄ in Fig. 4.

Control means actuated by a coin in second position includes a device such as the switch 50, Fig. 1, having a contact blade 51 engaged by the coin-holding part 40, when the latter is elevated or moved by a coin in second position, so as to close against a companion contact blade 52 for control purposes hereinafter described.

The coin-moving lever means 25 is disposed in its normal position of Fig. 3 by spring means 55 having one end 56 anchored to an eccentric part of an extension 25a on lever 25, Fig. 1, and having its other end 57 anchored to the nut and bolt means 14, the part 25a of the lever passing out the bottom of the control chute and being bent around U-fashion for engagement with actu-

ating means such as the plunger 60 of an electromagnetic solenoid 61, Figs. 1 and 5, pin means 62 pivotally linking the plunger and actuating extension 25a, such that when the solenoid coil 61 is energized, plunger 60 will be attracted to draw the actuating extension 25a toward the right, whereby to advance lever 25 from the normal position of Fig. 3, to the advanced position of Fig. 4, lever 25 being quickly restored to normal position by spring 55 as soon as coil 61 is de-energized.

It is pointed out that a portion of the surface of projection 28 on lever 25 is relieved, as at 28a, Fig. 5, to clear the control switch means 33 during advance of lever 25.

In Fig. 6 is shown the preferred control means employed for a vending machine adapted to be operated by coins of several denominations, i. e. five-, ten-, and twenty-five cent coins. A coin-testing chute 10a and cooperating coin-control unit 12a are provided for five-cent coins or nickels; while similar units 10b—12b and 10c—12c, respectively, are provided for dimes and quarters, and excepting for the denomination of coin handled in each instance, these testing and control chutes correspond to chutes 10 and 12 in construction and operation.

Assuming that a five-cent coin is deposited in the first unit, it will lodge in first position to close a switch 70—71, which corresponds to the switch 30 of Fig. 2; contact 70 is grounded at Gr, and this operating ground is connected via contact 71 and conductor 72 to one terminal of a lever-release solenoid or coil 73 having its remaining terminal connected to power source or battery 74 grounded at Gr, so that this coil is energized, thereby attracting its armature 75 from locking position before projection 76 on manual actuating lever 77, so that the latter may be moved (clockwise) against its normal spring 78 by the customer, thereby causing switch-operating projection 79 on lever 77 to close switch contacts 80—81 and 82—83, comprising part of the actuating switch.

Closure of contacts 82—83 as aforesaid results in connection of ground Gr at the actuating switch means, via conductor 84 to one terminal of each of three coin-shifting coils 85a, 85b, 85c (corresponding to coil 61 of Fig. 5) for the nickel, dime, and quarter units, and each of these three coils will be energized from power or battery sources 86a, 86b, 86c, respectively.

Since there is a five-cent coin resting at first position in the first unit, this coin will be shifted by the coin-shifting lever in coin control unit 12a (corresponding to lever 25 of Figs. 3 and 4) to cause such coin to be advanced to second position (not illustrated in Fig. 6, but see Fig. 4), thereby closing the second-position switch 87a—88a and connecting ground Gr via conductor 89 to motor switch contact 90, which is normally opened from its companion contact 91 by reason of having its rider projection 90a riding on the periphery of the five-cent control disc 93.

Disc 93 is rotated by shaft 95, driven through speed reducer 96 by motor 97 connected to power source 98 grounded at Gr, with its other terminal connected to cycling switch contact 100 normally closed with its companion contact 101 by reason of the former's riding projection 100a resting in the deepest part of notch 102 of the cycling disc 103 on shaft 95, so that the motor 97 is given a momentary energization, because contact 101 is now connected via conductor 104 to actuating

switch contact 80, which is at this time closed with its grounded contact 81, since the actuating lever 77 is now operated. However, as soon as cycling disc 103 moves slightly to cause riding projection 100a to ride onto a higher portion of notch 102, contacts 100—101 open, stopping the motor but meanwhile causing contact 100 to engage with contact 105, which connects via conductor 106 to contact 107 of the actuating switch.

Up to the present in this description, actuating lever 77 has been held in advanced or operated condition, causing its switch-operating projection 79 to be held away from projection 108a on contact 108, as a result of which contacts 107—108 are biased open so long as lever 77 is held down by the customer.

In order to effect delivery of the merchandise, lever 77 must be restored to normal position (counterclockwise), either by action of its spring 78 if the handle is released, or by cooperation of the customer in so restoring it. Such restoration of lever 77 will result in closure of contacts 107—108, thereby connecting ground from Gr through said contacts and conductor 106, contacts 100—105 closed, to motor 97, so that the latter will again run for the duration of one revolution of shaft 95 and disc 103, until notch 102 comes around again to permit rider projection 100a to drop into the deep part of notch 102, thereby opening contacts 100—105 and stopping the motor (with starting contacts 100—101 again closed preparatory to the next cycling operation).

Meanwhile, it should be observed that coil 73 of the lever locking means has been de-energized by removal of the coin from first position, opening switch 78—71, and locking projection 76 on the lever will again be locked behind plunger 75, unless there should be another coin ready to drop into first position from chute 10a as soon as the first-mentioned coin is shifted as aforesaid, in which case the actuating lever 77 would merely be unlocked by the consequent and further energization of locking coil 73 upon movement of the second coin into first position as soon as the first coin leaves.

Up to this point in the cycle of operation, motor 97 will run for the duration of one revolution of shaft 95, causing disc 93 to make one corresponding revolution, thereby causing notch 94 to pass once beneath projection 90a, so that dispensing switch contacts 90—91 will be closed once, thereby energizing a dispensing means or coil 110 via conductor 111 from power source 112 grounded at Gr, which will cause an ejecting slide 113 to be advanced and returned by spring 117 to push an article of merchandise 114 from a stack 115 in housing 116, slide 113 being restored by said spring 117 as soon as the actuating coil 110 is de-energized by opening of contacts 90—91 responsive to movement of disc 93.

In the case where a dime is deposited, instead of a nickel, the operation is the same as just described, excepting of course that switch contacts 70b—71b will be closed at first position in control unit 12b, lever 77 being operated as in the case of a nickel, which results in the dime being shifted to second position to close contacts 87b—88b, thereby connecting ground from Gr via conductor 120 to dispensing contact 90b, which will be closed twice with its companion contact 91b during the revolution of disc 121 and its two notches 122—123, thus impulsing dispensing coil or means 110b twice via conductor 124 from power source 125, and causing two articles to be ejected from stack 115b.

In the case where a quarter is deposited in chute 10c, the operation is substantially the same as heretofore described, the difference being in the fact that contacts 70c—71c will be closed in first position of the quarter in control unit 12c to release or unlock the lever 77 via conductor 72; and contacts 87c—88c will be closed by the quarter in second position, thereby connecting operating ground from Gr via conductor 130 to motor switch contact 90c, which will close five times with its companion contact 91c during one revolution of disc 131 and its five notches 132, which will cause dispensing coil 110c to be impulsed five times via conductor 133 from power source or connection 134, resulting in the ejection of five articles of merchandise from stack 115c in the manner heretofore particularly described in the case of the nickel unit.

Various modifications of the foregoing arrangement will occur to those skilled in the art, such as the use of a single testing chute 10 of the type adapted to handle nickels, dimes, and quarters; or the ejection of a single article, instead of one, two, or five articles, from the stacks 115, 115b, 115c, by having only one notch in the corresponding control discs 93, 121, and 131, in cases where only one article is to be dispensed for values of five, ten, and twenty-five cents. All such changes and modifications are contemplated within the scope of the appended claims.

I claim:

1. Coin control apparatus adapted to control electrically actuated dispensing means, and comprising: electrically actuated switch means and normally incomplete circuits therefor for actuating said dispensing means, electrically controlled main operating means for actuating said electrically actuated switch means, and a coin control adapted to receive a coin in a first position, coin switch means actuated by a coin in said first position and conditioning said main operating means for operation, electrically operated means for transporting said coin from first to second position responsive to operation of said main operating means, a second coin switch means actuated by a coin at second position to complete said dispensing switch circuits for operation by said electrically operated dispensing switch means, and means cooperable with said transporting means for preventing movement of a coin back toward first position from said second position.

2. Coin control mechanism comprising a coin chute having a coin entrance and exit, a lever oscillatable across the chute and normally disposed to receive a coin from said entrance, coin holding means adjacent said lever and cooperable with the latter, responsive to advance of the lever from said normal position, to hold a coin against movement toward said exit or back toward said entrance, a switch disposed for operation by a coin engaging said lever in said normal position, a second switch actuated by said holding means when a coin is held thereby, and means for oscillating said lever.

3. A coin control device including a chute having a vertical coin receiving passage and a vertical coin discharge passage offset horizontally from said receiving passage, a coin lever oscillatable from a normal position at the bottom of said receiving passage to advanced position toward said discharge passage, means on said lever for displacing a coin received thereon toward said discharge passage when the lever is advanced, coin holding means adjacent the advanced position of said lever and said discharge passage and coop-

erating with said lever to hold a coin advanced thereby against movement into said discharge passage, means for oscillating said lever from normal to advanced position and back, and control switch means actuated by a coin in said chute in said advanced position thereof, said coin holding means cooperating with the lever for holding a coin and preventing retrograde movement of the coin from said advanced position, said lever having means acting upon a coin held in advanced position to dislodge said coin for movement into said discharge passage when said lever is moved toward advanced position from normal position.

4. Coin control means comprising an oscillatable member, means for oscillating said member from a normal to an advanced position in a vertical plane, chute means gravitatingly guiding a coin into received position upon said oscillatable member in said normal position, means on said oscillatable member for carrying said received coin therewith upon movement to advanced position, yieldable coin engaging and holding means at said advanced position holding a coin thereat upon advance thereto and further holding said advanced coin upon return of said oscillatable member to normal position, means on said oscillatable member engaging an advanced, held, coin, when said oscillatable member is in normal position, and cooperating with said holding means, to prevent retraction of an advanced, held coin, and further acting upon said advanced, held, coin to dislodge and release said coin responsive to movement of the oscillatable member in a direction from normal toward advanced position, and switch means actuated by said holding means when a coin is held thereby as aforesaid.

5. Control switch means for actuating one or a plurality of dispensers and comprising: a plurality of dispenser actuating switches having a common motor for operating the same simultaneously, a coin-control unit for each dispenser switch; each said unit having at least two coin stations and each station having a coin-operated switch thereat, means for guiding deposited coins into the first station for each said unit, electrically actuated transporting means operated by a coin switch at the first station for moving said coin to the second station to operate the coin switch thereat, and establish an operating circuit for the corresponding dispenser switch, a master switch common to all said units, electromagnetic release means for said master switch and connected in a common circuit with all of the first-station coin switches for actuation by a coin at first station in any said unit, circuit connections controlled by operation of said master switch for actuating said transporting means, and circuit means controlled by said master switch for energizing said common motor to actuate said dispenser switches.

6. A coin-control unit comprising a chute body

having a vertical chute passage, a transport lever pivoted beneath said passage to oscillate transversely of the latter, said lever having an arcuate upper edge disposed below said passage when the lever is in a normal position to receive a coin of certain diameter thereon at a first station, a first switch on said unit and operated by a coin at said first station, a second switch at a second station situated laterally of the passage opposite said first station, yieldable coin-holding means at said second station and spaced upwardly of said arcuate edge on the lever, a coin-holding seat in said arcuate edge opposite said holding means when the lever is in normal position, mechanism for oscillating said lever, the latter having a coin-engaging formation displaced therewith to engage and transport a coin from the first station to the second station on movement of the lever from normal position, said coin being engaged and held by said holding means if the coin is at least of said predetermined diameter, on return of the lever to normal position, said coin-holding means and seat cooperating to prevent retraction of said coin from the second station, and said second switch means co-acting with said holding means for actuation by coin-effected movements of the latter.

7. In a coin-control unit, an oscillatory coin carrier movable back and forth from a normal coin-receiving to an advanced coin-holding position, means for moving the carrier back and forth, means at said advanced position engaging a coin moved thereto to hold the advanced coin against retractive movement toward said normal position, switch means operated by a coin at said normal receiving position, and switch means actuated by said coin-holding means dependently upon holding engagement thereof with a coin.

SAM MAY.
